(57) **CLAIM**

The ornamental design for a high chair, as shown and described.

DESCRIPTION

FIG. 1 is a perspective view of the high chair;
FIG. 2 is a front-side view of the high chair;
FIG. 3 is a rear-side view of the high chair;
FIG. 4 is a right-side view of the high chair;
FIG. 5 is a left-side view of the high chair;
FIG. 6 is a top view of the high chair;
FIG. 7 is a bottom view of the high chair; and,
FIG. 8 is perspective view of the high chair in disassembled position.

The broken line showing of portions of the high chair is included for the purpose of illustrating environmental structure and forms no part of the claimed design.
